UNITED STATES PATENT OFFICE.

EDGAR DOIZÉ AND ALBERT DUCOMBS, OF NEW ORLEANS, LOUISIANA.

DISPLAY-STAND.

SPECIFICATION forming part of Letters Patent No. 770,172, dated September 13, 1904.

Application filed April 6, 1904. Serial No. 201,897. (No model.)

To all whom it may concern:

Be it known that we, EDGAR DOIZÉ and ALBERT DUCOMBS, citizens of the United States, residing at New Orleans, in the parish of Orleans and State of Louisiana, have invented new and useful Improvements in Display-Stands, of which the following is a specification.

This invention relates to display-stands designed with special reference to supporting and advantageously displaying hats, and particularly those worn by ladies, the stand being so constructed that it adjusts itself to hats of different shapes and sizes and enables millinery to be effectively supported and held thereby. The construction also enables the spring-arms thereof to be removed and replaced when broken or injured without requiring the services of an expert mechanic.

With the above and other objects in view the invention consists in the novel construction, combination, and arrangement of parts, as herein fully described, illustrated, and claimed.

In the accompanying drawings, Figure 1 is a perspective view of a display-stand embodying the present invention. Fig. 2 is a plan view of the same with the cap removed. Fig. 3 is a vertical sectional view of the same, showing the manner of securing the spring-arms.

Like reference-numerals designate corresponding parts in all the figures of the drawings.

Referring to the drawings, 1 designates a standard which is preferably in the form of a tube. Adjacent to the upper end of the standard the latter is provided with a cup-shaped or cylindrical arm-supporting rim 2, provided with a bead or shoulder 3, extending around the outside thereof, while above the bead the rim is provided with a series of holes 3', through which pass a corresponding series of spring-arms 4, each of which is preferably composed of spring-wire of suitable gage having its inner end bent at an angle, as shown at 5, so as to extend downward within the upper end of the tubular standard 1, as clearly shown in Figs. 2 and 3. The bent inner ends of all of the spring-arms 4 are inserted in the upper

end of the tubular standard 1 and are firmly secured and held by means of a suitable plug 6, which is inserted or driven into the upper end of the standard, as shown in Fig. 3. Outside of the rim 2 each arm is coiled, as shown at 7, to provide the necessary vertical elasticity thereto and is then preferably extended upward at an angle, as shown at 8. As the outer end of the arm is approached the wire is bent in substantially a horizontal direction, as shown at 9, and then provided with one or more coils 10, which extend transversely of the length of the arm, while the extremity of the wire is bent abruptly outward, as shown at 11, and sharpened to form a short projecting impaling-point, which is located outside of and projects beyond the coil or coils 10, so as to engage and securely hold a hat placed upon the spring-arms. While the point or barb 11 impales the hat, the coil or coils 10 serve as a stop and prevent the passage of the point or barb 11 through the hat, so as not to injure the same.

Associated with the upper portion of the rim 2 is a cap 12, provided with a flange 13, which extends over the rim 2 and is provided in its lower edge with notches 14, corresponding with the location of the holes 3 and position of the arms 4, the said notches 14 receiving the spring-arms 4 in the manner shown in Figs. 1 and 3, said cap acting as a closure for the cup-shaped rim, thus concealing the upper end of the standard, the plug 6, and the inner portions of the spring-arms, while allowing access to be had thereto for the purpose of detaching any one or more of the spring-arms and replacing the same. If desired, the cap 12 may be secured at one or more points by drops of solder, which form a temporary seal between the cap and rim, but allow the cap to be easily removed when necessary.

From the foregoing description it will be seen that the stand is adapted to support and securely hold a hat of any size or shape without the necessity of pinning the hat on the stand, as is usually found necessary with the ordinary construction of hat-holders.

Should one of the arms break, it can be removed and easily replaced by another at small

cost. The spring - arms may of course be made of wire of any suitable gage, and the coils 7 and 10 may be increased or diminished in number to suit the will of the manufacturer. These and other changes in the form, proportion, and minor details of construction may be resorted to without departing from the principle or sacrificing any of the advantages of the invention.

10 Having thus described the invention, what is claimed as new is—

1. A display-stand comprising a standard, spring-arms radiating therefrom, an arm-supporting rim on the standard, and a plug inserted in the upper end of the standard and acting to bind the inner ends of all the arms in place.

2. A display-stand comprising a standard, radial spring-arms having bent inner ends inserted in the standard, a plug inserted in the upper end of the standard and engaging the bent inner ends of all the arms, and a rim en-

circling the standard and forming a support for the arms.

3. A display-stand comprising a standard, 25 a cup-shaped device thereon having holes formed at intervals of its sides, radial spring-arms connected to the standard and passing through said holes, and a cap fitted to said device, having notches in which portions of 30 the arms are received.

4. A display-stand comprising a standard, a cup-shaped rim thereon, radial spring-arms connected to the standard and passing outward through the rim, and a flanged arm-retaining cap fitted to the upper portion of the rim and engaging the arms. 35

In testimony whereof we affix our signatures in presence of two witnesses.

EDGAR DOIZÉ.

ALBERT DUCOMBS.
